CLAIM

The ornamental design for the outsole for footwear, as shown and described.

DESCRIPTION

FIG. 1 is a first perspective view of my ornamental design for an outsole for footwear;

FIG. 2 is a second perspective view thereof;

FIG. 3 is a right side view thereof;

FIG. 4 is a left side view thereof;

FIG. 5 is a front view thereof;

FIG. 6 is a rear view thereof;

FIG. 7 is a bottom view thereof;

FIG. 8 is a top view thereof;

FIG. 9 is an enlargement of the tread detail shown at the heel portion of the outsole labeled "9" in FIG. 1; and,

FIG. 10 is an enlargement of the tread detail shown at the toe portion of the outsole labeled "10" in FIG. 1.

The broken lines in the drawings are used to show portions and environment that form no part of the claimed design. The thicker broken lines in FIG. 1 are used to identify areas of enlargement and also form no part of the claimed design.

1 Claim, 9 Drawing Sheets(56)
